US00D960191S

(12) **United States Design Patent** (10) Patent No.: **US D960,191 S**
Feit et al. (45) Date of Patent: **** Aug. 9, 2022**

(54) **DISPLAY SCREEN WITH GRAPHICAL USER INTERFACE**

(71) Applicant: **HONDA MOTOR CO., LTD.**, Tokyo (JP)

(72) Inventors: **Steven Feit**, Dublin, OH (US); **David Vanderburgh**, Dublin, OH (US); **Ross Miller**, Hilliard, OH (US); **Koo Ho Shin**, Huntington Beach, CA (US)

(73) Assignee: **HONDA MOTOR CO., LTD.**, Tokyo (JP)

(**) Term: **15 Years**

(21) Appl. No.: **29/681,564**

(22) Filed: **Feb. 26, 2019**

Related U.S. Application Data

(62) Division of application No. 29/590,076, filed on Jan. 6, 2017, now Pat. No. Des. 841,673.

(51) **LOC (13) Cl. 14-04**

(52) **U.S. Cl.**

USPC **D14/488**

(58) **Field of Classification Search**

USPC D14/485-495
 CPC B60K 37/00; G06F 3/0482; H04N 1/00408
 See application file for complete search history.

(57) **CLAIM**

The ornamental design for a display screen with graphical user interface, as shown and described.

DESCRIPTION

FIG. 1 is a front view of a display screen with graphical user interface showing a first embodiment our new design; FIG. 2 is a front view of a second embodiment thereof; FIG. 3 is a front view of a third embodiment thereof; and, FIG. 4 is a front view of a fourth embodiment thereof. The broken lines showing the remainder of the display screen, as well as those showing portions of the graphical user interface, are for environmental purposes only and form no part of the claimed design.

1 Claim, 4 Drawing Sheets
